UNITED STATES PATENT OFFICE

149,200

DESIGN FOR A DRAFTING TEMPLET

Raymond I. Martin, South Bend, Ind., assignor
to Keuffel & Esser Company, Hoboken, N. J., a
corporation of New Jersey

Application April 6, 1946, Serial No. 128,335

Term of patent 14 years

(Cl. D52—1)

To all whom it may concern:

Be it known that I, Raymond I. Martin, a citizen of the United States, residing at South Bend, in the county of St. Joseph, State of Indiana, have invented a new, original, and ornamental Design for a Drafting Templet, of which the following is a specification, reference being had to the accompanying drawing, forming part thereof.

Fig. 1 is a plan view of a drafting templet, showing my new design; and

Fig. 2 is an edge view thereof.

I claim:

The ornamental design for a drafting templet, as shown.

RAYMOND I. MARTIN.
